UNITED STATES PATENT OFFICE.

CARL GUSTAV HERMANN REMANÉ, OF BERLIN, GERMANY, ASSIGNOR TO GENERAL ELECTRIC COMPANY, OF SCHENECTADY, NEW YORK, A CORPORATION OF NEW YORK.

DEVICE FOR INCANDESCENT LAMPS WITH METAL FILAMENTS.

1,145,213.

Specification of Letters Patent.

Patented July 6, 1915.

Application filed March 30, 1910. Serial No. 552,368.

To all whom it may concern:

Be it known that I, CARL GUSTAV HERMANN REMANÉ, a subject of the German Emperor, and a resident of Berlin, Germany, S. W. Planufer 14, have invented a certain new and useful Improvement in Devices for Incandescent Lamps with Metal Filaments; and I do hereby declare the following to be a full, clear, and exact description of the invention, such as will enable others skilled in the art to which it appertains to make and use the same, reference being had to the accompanying drawings, and to letters of references marked thereon, which form a part of this specification.

This invention has for its object to overcome the deleterious effects resulting from the oscillations of filaments in incandescent lamps and consists in providing a check or obstacle intermediate of the length of the filament so as to prevent development of the oscillations or of reducing the amplitude.

In the drawings, Figure 1 illustrates a vibrating filament supported at one end only. Fig. 2 shows a vibrating filament supported at both ends. Fig. 3 illustrates a vibrating filament supported at both ends and provided with a check or obstacle applied at one point intermediate of the filament; Fig. 4 illustrates a lamp having four lengths of filament and provided with obstacles intermediate of each; four possible variations being visualized in this one figure, and Fig. 5 shows the obstacle in the form of a helical spring.

In the drawings, α is the lamp stem, l is the filament, g indicates the lines of vibration, p^1, p^2, p^3, p^4 are the filament supports, b, d are the supports for the check carrying arms; c^2, c^3, c^4, g^2 are the arms; $o, o^1, o^2, o^3, o^4, o^5, o^6$ are the checks or obstacles operative upon the filament; r is a tubular obstacle, and r^1 a helical spring.

In incandescent lamps with loop shaped metal filaments, shocks or rhythmic vibrations can lead to oscillations of the filaments, which oscillations differ according to the special arrangement of the points of fastening or supporting of the filament loops. A filament loop which is held merely at the current supply points by soldering, cementing or clamps, and has no other points of support, will oscillate as shown in Fig. 1, in the same way as a kind of tuning fork.

If at the loop point or bend of the filament there is provided a support, the oscillations will be similar to those shown in Fig. 2, which eventually may combine with oscillations of the kind first referred to.

The substance of this invention consists in obviating oscillations of metal filaments of incandescent lamps, or in considerably limiting and rendering them harmless, by providing an obstacle for the development of such oscillations, or at least by considerably reducing their amplitude. This is effected by surrounding the filaments near the non-yielding points of securing (p^1, p^2, p^3, p^4 Fig. 4) with loops or eyes (o^1, o^2, o^3, o^4) of sufficiently small diameter, so that a second node of oscillations is provided at the point where these loops are arranged, or at an adjoining point (Fig. 3, o). Owing to this strongly unsymmetrical sub-division of the filament loop, the filament is divided into two or three parts, which, owing to their different lengths get a very different duration of own oscillations, and therefore, interfere with each other by dissonance when oscillations take place (Fig. 3). At the same time, owing to this arrangement, the appearance of oscillation resonances is altogether rendered more difficult. The amplitudes taking place are reduced, and the danger of a thread breaking is considerably reduced by these devices.

If only one loop or eye is used for each filament branch, the said loops are preferably arranged fairly near the points of securing (Fig. 4, o^1, o^2). If two such oscillations-damping devices are used for each different branch, they are preferably arranged as near as possible to the existing points of the greatest rigidity or of the greatest bending momentum (Fig. 4, on the left, o^3, o^4, o^5, o^6). These eyes or loops (Fig. 4, o^1, o^2, o^3, o^4) can be supported either by the stem of the filament-supporting frame (c^2, c^4) or by the supply wires (c^3), or the eyes or loops can be formed by the opening of a tube r , or by a helical spring r^1 —which surrounds the bottom portions of the filament loops. The said eyes or loops can further be held by supports of a springy material, in order to enable them to follow small movements in the direction of the filament, in case the filament should get fritted or burnt to the eyes.

What I claim is:—

Means for supporting filaments for incandescent lamps comprising a main supporting member, end supporting members carried by said main supporting member, said end supporting members being adapted to hold a filament in a relatively fixed position, a stop located adjacent to the filament at a point close to one of said end supporting members 10 and adapted upon contact with the filament when vibrating for its full length to set up therein secondary vibrations of different lengths, said stop being insulated from the lamp circuit and normally out of contact 15 with the filament, but sufficiently close there-

to laterally to be momentarily touched thereby as the filament is subjected to vibrations whereby the free vibration of the filaments between its supports will be interfered with by the counteracting force of vibrations of a different character, the filament being thus restored to an approximately non-vibrating condition. 20

In testimony whereof I affix my signature in presence of two witnesses.

CARL GUSTAV HERMANN REMANÉ.
